UNITED STATES PATENT OFFICE.

FREDERICK WILLIAM HOFMANN AND FRANCIS J. DILLMAN, OF PHILADELPHIA, PENNSYLVANIA, ASSIGNEES TO THE PHILIP J. RITTER CONSERVE COMPANY.

DESIGN FOR A BOTTLE.

SPECIFICATION forming part of Design No. 22,423, dated May 9, 1893.

Application filed April 8, 1893. Serial No. 469,612. Term of patent 7 years.

To all whom it may concern:

Be it known that we, FREDERICK WILLIAM HOFMANN and FRANCIS J. DILLMAN, citizens of the United States, residing in the city and county of Philadelphia, State of Pennsylvania, have invented and produced a new and original Design for a Bottle, of which the following is a specification, reference being had to the accompanying drawing, forming part thereof.

The leading features of our design for a bottle are the body thereof of conical form, a breast of swelled form with circumferential beads on the base of the same, and circumferential beads near the bottom of the body, a spiral bead on the periphery of the neck, and a plain portion on the neck above said spiral bead.

In the drawing: A designates a bottle consisting of the body B, the breast C and the neck D. The breast is of swelled form, and the body of conical form, said breast and body being circular in cross section. At the base of the breast are circumferential beads E and on the body above the bottom thereof are circumferential beads F. On the neck D is a spiral bead or single thread G, and above the latter is a plain portion H.

What we claim is—

The design for a bottle substantially as shown and described.

FREDERICK WILLIAM HOFMANN.

FRANCIS J. DILLMAN.
